VALVE BODY

Edward B. Myers, Oreland, Pa., assignor to Minneapolis-Honeywell Regulator Company, Minneapolis, Minn., a corporation of Delaware

Filed Sept. 27, 1962, Ser. No. 71,887

Term of patent 14 years

(Cl. D91—3)

FIG. 1

FIG. 2

FIG. 3

FIG. 1 is a perspective view of a valve body showing my new design;

FIG. 2 is an elevation view in cross-section, looking in the direction of the arrows on line 2—2 of FIG. 1.

FIG. 3 is a right end elevation of the valve body.

The undisclosed side is substantially the same as the side shown, and the bottom is substantially the same as the top.

I claim:

The ornamental design for a valve body, substantially, as shown and described.
